CLAIM

The ornamental design for a spray unit, as shown and described.

DESCRIPTION

FIG. 1 is a front view of the spray unit of the present invention without the cover;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view of the spray unit of the present invention, shown at a reduced scale showing the cover removed from the body of the spray unit.

The opposite side of the cover is a mirror image of that shown.
